UNITED STATES PATENT OFFICE.

GEORGE STANLEY MEIKLE AND HENRY D. MACKAYE, OF DETROIT, MICHIGAN.

OIL BURNER.

Application filed February 9, 1925. Serial No. 7,818.

This invention relates to oil burners, and more particularly to burners which have rotating nozzles or burner tips.

This invention has, for its object generally to provide an improved construction and arrangement of parts which is efficient, economical and readily manufactured.

A specific object of the invention is to provide a burner having a rotating burner tip so arranged, when rotating, as to cause a very complete atomization of the heavier fuel oils and a thorough mixing with air to form a combustible mixture.

Another object of the invention is to provide an oil burner having a rotating tip with an arrangement for feeding or picking up the oil in a liquid state and converting it into a highly atomized combustible mixture.

Still another object is to provide a burner which is safe for use in domestic furnaces and is readily installed and adjusted.

Other objects of the invention will in part be obvious and will in part appear herein-after.

The invention accordingly comprises the features of construction, combinations of elements, and arrangement of parts, which will be exemplified in the constructions hereinafter set forth and the scope of the application of which will be indicated in the claims.

For a fuller understanding of the nature and objects of the invention, reference should be had to the following detail description taken in connection with the accompanying drawings, in which:

Figure 1 shows, mainly in vertical section, the parts of a burner arranged in accordance with the invention;

Fig. 2 shows, mainly in elevation, parts being broken away, a view of the underside of the cap of the burner cup;

Fig. 3 shows, mainly in side elevation, the pick-tube as used in the burner shown in Fig. 1;

Figs. 4 and 5 are fragmentary sectional views showing modifications.

Referring now to the drawings, 10 notes an electric motor which is preferably directly coupled to drive the shaft 11, which as shown is disposed vertically and is journaled to revolve in the central hub 12, of the oil well casing 13. The upper end of shaft 11 projects beyond the hub 12 and

has secured thereto a burner cup 14 and a cap 15; the cap and cup being so arranged as to be revolved together by the shaft 11 and to provide peripheral openings therebetween, as shown clearly at 16. This peripheral opening constitutes the burner "orifice" from which issues an annular sheet-like flame when the burner is in operation.

The oil well casing 13 is stationarily supported by means of a plurality of legs, for example by three legs such as are shown at 17, and are preferably made collapsible by providing extensible lower sections 18 secured in place on the upper sections by means of lock-nuts as shown at 19. These legs are shown also as having feet 20 secured to blocks 21, the latter being preferably made of resilient or shock-absorbing material. In consequence the vibration incident to the rotation of the burner parts is substantially absorbed and not transmitted to the floor or other support for the burner structure.

The oil well casing is preferably provided with a plurality of interior horizontal diaphragms, for example as shown at 22 and 23 respectively, which divide the interior into a lower chamber, an intermediate chamber and an upper chamber respectively. The lower chamber comprises the oil well proper, on the floor of which are a plurality of radially disposed webs 24, which prevent the oil therein from being set into rotation. The lower diaphragm 22 is also preferably provided with a depending annular web 25 which serves to break up crests and wave that might otherwise form on the oil surface in the oil well. Each of these diaphragms is preferably provided with one or more openings, as shown at 26 and 27 respectively.

The diaphragms extend radially inwardly from the outer wall of the oil well casing but terminate sufficiently short to clear an annular skirt 30 when rotating which extends down from the bottom of the burner cup 14. Within the depending skirt is preferably provided the means for raising or picking up the oil from the oil well and supplying it in atomized form to the interior of the burner cup.

In the form of burner illustrated in Fig. 1 this means comprises a plurality of what may be termed "pick-tubes" 31, which are

secured in the bottom of the cup 14 and have their upper ends closed but project sufficiently above the bottom of the burner cup so as to have side openings 32 from which issues the atomized oil when the cup is rotated. These pick-tubes have their lower ends 33 formed so as to skim the surface of the oil in the oil-well and lift a spray by the velocity principle (i. e., that the height to which a body can be raised is proportional to the square of the relative velocity). The construction will be made clear by reference to Fig. 3. The cup has air-holes 34 formed in its bottom to admit air for combustion.

The cap 15 is likewise preferably provided with radial webs 35 which depend into the interior of the burner cup and tend to prevent interior whirling of the combustible mixture within the cup.

It is generally preferable to provide some form of air regulating means, so that the air for combustion may be proportioned to the character of oil being used as fuel. For this purpose an air controlling member is arranged to surround the burner cup, and as shown comprises a collar 36, which has an interior flange 37 arranged to cooperate with the upper wall of the oil-well casing to provide an air chamber thereabove for supplying air to the openings 34. On its outside upper edge the collar has an upstanding saw-toothed cylindrical ring 38 which cooperates with a similar ring 39 on the annulus 40; the latter being movably disposed upon the ring 38 and extended inwardly but clears the outer wall of cup 14 thereby substantially closing in the top of the air chamber. The ring 39 on annulus 40 as shown is made to fit within the ring 38, so that when the saw teeth are in register, the series of air openings thus provided are opened to their maximum degree. When the annulus 40 is turned so to move the teeth as far out of register as possible, the air feed openings are reduced or substantially closed.

The collar 36 is shown as provided at its lower end with an outwardly extending flange 41, while the flange 37 is so positioned with respect to a saucer-shaped flange 42, formed beneath on the oil-well casing, that any oil which may get onto the collar 36 will drip into the saucer 42.

The saucer 42 will also catch any oil which may flow over the outside of the oil-well casing by reason of the flooding of the burner, or from the burner cup, in case the flame becomes extinguished.

The saucer 42 is accordingly provided with an overflow connection 43 which preferably leads to the float chamber 44 having a float 45 arranged to actuate a shut-off valve 46 in the main oil supply pipe 47, shown as leading from a convenient oil supply source 48 to the bottom of the oil well casing 13. The

oil supply source is also preferably provided with means such as shown at 49 for regulating the oil level in the oil-well, thereby normally preventing its being flooded.

The operation of the burner thus far described is as follows: The oil-well is supplied with oil from the source 48 so that a constant level is substantially kept therein at all times. When it is desired to use the burner, the motor 10 is started up and the burner cup made to revolve at a moderately high speed. (Speeds of substantially 3400 R. P. M. have been found sufficient to produce the desired atomizing effect, and are preferable to very high speeds which produce much noise and excessive wear and tear.)

The pick-tubes, in consequence of their velocity with respect to the oil, pick up a spray and raise it with a steady urge; the spray, as it accelerates in rising within the pick-tube, encounters the barrier closing off the upper end of the tube, becoming thereby broken into very fine particles which are drawn out at the side openings 32 under the influence of the centrifugal force produced by the rotation of the cup. The oil thus atomized mixes with the air entering through the openings 34 to form a combustible mixture which issues at a relatively high velocity from the annular burner orifice 16. When ignited this produces an annular sheet of flame.

The upper and intermediate chambers in the oil-well casing serve as receptacles to intercept any spray splashed up from the lower chamber, also they serve to catch any spray which may tend to be thrown off from the skirt 30. The oil thus caught is returned to the oil-well through openings 26 and 27. The generally conical shape shown for the upper wall of the oil-well casing is also advantageous in this connection.

The operation of the air regulation and the safety features are believed to be sufficiently set forth above in connection with the description of their construction so that further comment is unnecessary.

In the modification shown in Fig. 4 the depending skirt 50 of the cup 14 is provided with an interiorly projecting formation which serves as the "oil-pick". As shown this comprises a vertically extending web which is generally radial in inward configuration, but may be slightly dished to serve better as a trough to convey the oil spray. The lower end of the web is shown as scoop-shaped at 52 so that upon rotating the cup, the scoop 52 will lift a spray which will rise into the cup 14 by way of opening 53. Across the upper end of the web 51 just a little above the opening 53 is a short overhung flange 54, against which the spray dashes and is finely broken up; an opening in the flange 54 is also provided at 55 to allow the resulting atomized spray to issue

under the influence of centrifugal force to form a combustible mixture in the cup 14.

In the modification shown in Fig. 5, the skirt 60 of the cup 14 has a spiral groove 61 formed therein, the groove having an elongated projection 62 arranged to skim the oil surface and pick up spray. The spray thus raised by the spiral groove has a longer path in which to accelerate before it enters the burner-cup by way of opening 63, and dashes against the partition 64 arranged to effect the atomization by impact and the sudden arresting of the spray particles as above pointed out.

15 While three forms of oil lifting means have here been described, obviously other arrangements with or without the skirt on the burner cup may be arranged to lift the oil in accordance with the velocity principle, 20 such for example as scoops. Likewise webs such as shown at 51 may be pressed in or attached to the skirts instead of being made integral therewith.

25 Since certain changes may be made in the above construction and different embodiments of the invention could be made without departing from the scope thereof, it is intended that all matter contained in the above description or shown in the accompanying drawing shall be interpreted as illustrative and not in a limiting sense.

It is also to be understood that the following claims are intended to cover all of the generic and specific features of the invention 35 herein described, and all statements of the scope of the invention which as a matter of language might be said to fall therebetween.

Having described our invention, what we 40 claim as new and desire to secure by Letters Patent, is:

1. In an oil burner structure, the combination with an oil well, of a rotatable nozzle having oil lifting means projecting into said well displaced from the axis of said nozzle arranged to move with the rotation of said nozzle and to raise an oil supply therefrom by the relative velocity of said means with respect to said well, means for rotating said nozzle, and means for atomizing the lifted oil by impact disposed in operative conjunction with said oil-lifting means.

2. In an oil burner structure, the combination with an oil well, of a rotatable nozzle having a tubular projection arranged to dip into said well, said projection being provided with a tip arranged to dip slightly beneath the oil level and raise an oil spray and conduct the same into said nozzle, power means for rotating said cup, and barrier means in said nozzle disposed in the path of the entering spray whereby atomization is produced by impact.

3. In an oil burner structure, the combination with an oil well casing provided with

a vertical rotatable shaft, of a burner cup secured to said shaft and having means extending downwardly therefrom into said oil well casing and arranged to lift an oil spray therefrom by the relative velocity of said means with respect to said well when rotated, power means for rotating said cup, and means in said cup for atomizing the said spray by impact disposed in operative conjunction with said oil lifting means. 75

4. In an oil burner structure, the combination with an oil well casing, provided with a vertical rotatable shaft, of a burner cup secured to the upper end of said shaft having a tubular device extending downwardly therefrom into said oil well casing and arranged to have its tip dip below the oil level to lift an oil spray therefrom by the movement of said tubular device when rotated, power means for rotating said cup, 80 and barrier means in said cup for atomizing said spray disposed above and across the entry of said spray into said cup. 85

5. In an oil burner structure, the combination with a chambered oil well casing provided with a vertical rotatable shaft, of a burner cup secured to the upper end of said shaft and having a cap disposed thereon to provide an annular burner orifice, a plurality of pick-tubes extending from the bottom of said burner cup and provided with tips arranged to skim the surface of the oil in said casing and to lift a spray therefrom, said tubes extending into said burner cup and provided with lateral openings and a sealed upper end, and power means for rotating said vertical shaft. 90

6. In an oil burner structure, the combination with a chambered oil well casing provided with a vertical rotatable shaft, of a burner cup secured to the upper end of said shaft and having a cap disposed thereon to provide a nozzle orifice, said cup being provided with skirted means depending into said chambered casing and interiorly provided with oil-lifting means, said oil-lifting means being provided with an oil entrance to said burner cup and an impact barrier disposed across said orifice whereby to produce substantially complete atomization of the lifted oil, power means for rotating said cup, and means for regulating the air supply to said burner. 105 110 115

7. In an oil burning structure, the combination with a chambered oil well casing, of a burner cup having air openings in its under side disposed rotatively above said casing, means on said cup displaced from the axis thereof and projecting into said casing adapted for lifting oil when said cup is rotated, said means being provided with a formation adapted to atomize said oil by impact and disposed in operative conjunction with the entrance of said means to said cup, 120 additional means associated with said cup 125 130

for drawing air through said openings when said cup is rotated, and power means for rotating said cup.

8. In an oil burner structure, the combination with a chambered oil well casing, of means for supplying oil thereto, a burner cup rotatably disposed above said casing and provided with a plurality of oil pick-tubes extending into said casing and arranged to lift oil therefrom, means in said burner cup cooperating with said pick-tubes for atomizing the oil lifted thereby, means for supplying air for combustion, and power means for rotating said burner cup.

9. In an oil burner structure, the combination, with a chambered oil well casing, of means for supplying oil thereto, a burner cup rotatably disposed above said casing and provided with a plurality of oil pick-tubes displaced from the axis of said cup and extending into said casing, means for atomizing the lifted oil by impact disposed in operative conjunction with said tubes, means for rotating said burner cup, and means disposed on said casing about said cup for regulating the admission of air for combustion.

10. In an oil burner structure, the combination with a chambered oil well casing, of means for supplying oil thereto, a burner cup rotatably disposed above said casing and provided with a plurality of oil pick-tubes extending into said casing, said tubes being formed and arranged to lift and atomize oil therefrom, means for preventing the whirling of oil in said casing, means for preventing the whirling of the combustible mixture in said cup, and means for rotating said burner cup.

11. In an oil burner structure, the combination, with a chambered oil well casing, of means for supplying oil thereto, a burner cup rotatably disposed above said casing and provided with a plurality of oil pick-tubes displaced from the axis of said cup and extending into said casing, means for atomizing the lifted oil by impact disposed in operative conjunction with said tubes, means for rotating said burner cup, means disposed on said casing about said cup for regulating the admission of air for combustion, and means for regulating the oil supply and for automatically shutting off said oil supply when said casing is flooded.

12. In an oil burner structure, the combination with a chambered oil well casing, of means for supplying oil thereto, a burner

cup rotatably disposed above said casing and provided with a plurality of pick-tubes extending into said casing, said tubes being formed and arranged to lift oil from said casing, means for atomizing the lifted oil by impact disposed in operative conjunction with said tubes, said oil well casing being formed with an inwardly tapered top portion adapted to protect against overflows and the like, and having means on the exterior thereof for catching said overflows, and means for rotating said burner cup.

13. In an oil burner structure, the combination with a chambered oil well casing, of a rotatable burner cup disposed thereabove, and means on said cup adapted for lifting and atomizing oil from said casing, said casing being provided with webbed partitions for breaking up surges, eddies and returning splashes.

14. In an oil burner structure, the combination with a chambered oil casing, of a burner cup rotatably disposed thereabove and provided with a plurality of oil pick-tubes projecting into said casing and adapted when moving relatively thereto for lifting oil therefrom and conveying it into said burner cup, power means for rotating said burner cup, a saucer-like receptacle provided on said casing and arranged to intercept oil overflow, and an air collar disposed about said burner cup and provided with a flange arranged to intercept oil spray thereof from said casing and to deflect the same into said saucer-like receptacle.

15. In an oil burner structure, the combination with a chambered oil casing, of a burner cup rotatably disposed thereabove and provided with a plurality of oil pick-tubes projecting into said casing and adapted when moving relatively thereto for lifting oil therefrom and conveying it into said burner cup, and adapted to lift an oil spray therefrom by the relative velocity of said pick-tubes with respect to said casing, an independently supported electric motor for rotating said burner cup, supporting means arranged to support said casing in operative relation to said motor, and an elastic shock-absorbing device affixed to said supporting means and arranged to absorb vibrations.

In testimony whereof we affix our signatures.

G. STANLEY MEIKLE.
HENRY D. MacKAYE.
